SIGNALING DEVICE

Leon N. Hampton, New York, N. Y., and Albert K. Smith, West Orange, N. J., assignors to Bell Telephone Laboratories, Incorporated, New York, N. Y., a corporation of New York

Application January 20, 1934, Serial No. 707,490

5 Claims. (Cl. 200—83)

This invention relates to pneumatic ticket distributing systems and more specifically to a pneumatically operated signaling device for use in such a system.

5 In pneumatic distributing systems of the type used in telephone exchanges for dispatching tickets, for example, delivery tubes are connected at their ends to so-called sending and receiving valves and the receiving valves in turn are connected to an air exhaust tube to the other end of which an air blower is connected for generating a current of air in the delivery tubes for propelling the tickets therein. In such a system, however, it is necessary to maintain the flow of air through these tubings at a constant predetermined velocity in order to assure the rapid arrival of the tickets at the receiving valves and to provide signaling devices for indicating the pressure difference in the ticket sending tubes 10 upon the accidental stoppage of the tickets therein and for signaling such a condition.

The object of this invention is to improve the construction and operation of such signaling devices.

25 According to this invention a diaphragm is clamped between two casing sections and serves to form therewith a common wall for two adjacently disposed air chambers each connected to a ticket sending tube. This diaphragm operates upon a maximum pressure difference in the ticket sending tubes, and therefore in the air chambers thus formed, for engaging contacts to cause the operation of signaling devices and the operation of an index on a scale for indicating the extent of variations of air pressure in the ticket sending tubes, means being provided to permit the initial adjustment of the diaphragm with respect to the air pressure in each sending tube and the adjustment of the contacts with respect to the adjusted position of the diaphragm with means in the form of a system of ports for maintaining the air pressure in the chambers proportional to that of the pressure in the ticket sending tubes upon the adjustment of the contacts and while the system is in operation.

Other features and advantages of the invention will appear from the following description and from the claims appended thereto, reference being had to the accompanying drawings in which

50 Fig. 1 is a front assembly view showing a number of operating parts with portions cut away;

Fig. 2 is a cross-sectional view taken on line 2—2 of Fig. 1;

Fig. 3 is a partial view showing a number of operating parts in section; and

Fig. 4 is a sectional view taken on line 4—4 of Fig. 2.

In the drawings, 10 is a diaphragm which is clamped between the circularly shaped flange portions of casings 11 and 12 to form therewith two air chambers CH and CH1 shown in Fig. 4. Diaphragm 10 is drilled at its center portion for receiving a rod 17 which serves for clamping the diaphragm 10 between two discs 13 and 14 under the action of screw nuts 15 and 16, the discs 13 and 14 being provided for limiting the effective or yieldable surface of the diaphragm 10 and thereby its amplitude of movement.

Rod 17 extends perpendicularly with respect to the plane of the diaphragm in the chamber CH and carries at its upper end portion a disc 18 engaging a forked lever member 19 secured at one end of a shaft 20. As shown in Fig. 2, this shaft is journaled at one end in a sleeve 22 mounted in the rear wall of chamber CH and at its other end in the sleeve 21 mounted in a bracket 9 which is in turn secured to the top wall of a third or auxiliary chamber CH2 as by screws 8 shown in Fig. 3, the vertically disposed wall or partition 46 between chamber CH and CH2 being provided with a drilled hole 45 through which the shaft 20 passes with a predetermined amount of clearance to form an air path provided for a purpose that will be hereinafter described in detail.

30 On that end of shaft 20 which extends in chamber CH2 is securely mounted a gear sector 23 shown in Figs. 2 and 3 disposed in operable relation with a pinion 24 formed at one end of a spindle 25 which is journaled at one end in a dial 27 and the other end in a bracket 26 secured to the rear face of the dial as by rivets 28. On the front disposed end of spindle 25 is securely mounted an index or pointer 29 for movement in juxtaposition to the face of the dial 27 35 having marks for indicating the operation of the diaphragm 10 upon a pressure difference in the chambers CH and CH1.

Dial 27 is held in adjusted position with respect to pointer 29 by a plug 30 threadedly engaging a cover plate 31 forming the front wall of chamber CH2. This cover plate is secured to the casing portion 11 by a number of screws such as 32 shown in Figs. 1 and 2, and a glass 33 is cemented in the plug 30 to prevent any escape of air at this point while permitting the visual observation of the pointer 29 and the marks on the dial 27. Gear sector 23 carries on one side thereof a lateral extending lug 34 carrying contact members 35 and 36 for engaging contact springs 55

37 and 38 depending upon the direction of operation of diaphragm 10 under a difference of air pressure in chambers CH and CH1. Contact springs 37 and 38 are held securely on the left side wall of chamber CH2 by similar screws 39 mounted in insulating bushings such as 40 for insulating them from casing portion 11, wire terminals 41 and 42 being provided for electrically connecting the contact springs 37 and 38 with signaling circuits not shown with which they form a part.

In chamber CH there is mounted a vertically disposed gear rack 50, shown in Figs. 2 and 4 guided in its vertical movement by a stud 52 threading in the partition or wall 46 and a stud 53 threading in the dome shaped portion of casing 11 and a tension spring 54 which is hooked at one end to the upper disposed end of rack 50 and the other end at the extremity of rod 17 is provided for tensioning the diaphragm 10 in that direction an amount proportional to that of the initial difference of air pressure in the ticket sending tubes due to their unequal length and direction. The operation of gear rack 50 and thereby the adjusted tension of spring 54 is effected by a pinion 51 formed integrally with a spindle 60 shown in Figs. 2, 3 and 4. This spindle is journaled at one end in a bearing portion 58 formed with the rear wall of casing 11 and the other end of this spindle is journaled in a sleeve 61 having one of its ends threadedly engaging a hub portion 65 formed with the partition 46. The hub portion 65 is filled with packing or fibers 62 disposed between the concave rings 63 and 64 the whole forming a stuffing box around spindle 60 to prevent any leak of air from chamber CH to chamber CH2 at that point, the packing and rings 63 and 64 being held tightly in the hub portion 65 through the screwing action of sleeve 61 which also serves to force the pinion 51 against the front end of the bearing portion 58 for holding it against movement under the tension of spring 54.

45 The sleeve 61 is supported at its front end portion by a bracket 56 in turn secured to lugs 47 in chamber CH2 by screws 48, this bracket being provided with screws 74 and 75, having camming portions in the form of pointed ends for engaging the contact springs 37 and 38 for adjusting them with respect to contacts 35 and 36 carried by gear sector 23.

55 The chamber CH1 is connected to a ticket sending tube not shown through a pipe 70 connected to an elbow shaped conduit 71 threadedly engaging the lower portion of casing 12 and chambers CH1 is connected to another ticket sending tube not shown through a pipe 72 connected to a nipple 73 secured in the wall of casing portion 11 as shown in Figs. 2 and 4. According to this construction any difference of air pressure in the ticket sending tubes and therefore in the air chamber CH and CH1 will cause the operation of the diaphragm 10 for operating pointer 29 on dial 27, and thereby indicating such pressure difference, the movement of the diaphragm within the limits defined by the springs 37 and 38 with respect to contacts 35 and 36 carried by gear sector 23 being effective to close the operating circuit of an audible or visual signaling device for indicating such a condition.

70 The balance in air pressure in chambers CH and CH1 acting on the diaphragm 10 is maintained upon the removal of the plug 30 as when 75 adjusting the contact springs 37 and 38 through

the movement of camming screws 74 and 75 as above described by providing a system of ports consisting of an air path running from chamber CH1, Figs. 1, 2 and 3 to chamber CH2 and therefore to chamber CH through hole 45 by a conduit 80 beginning in chamber CH1 and extending through the clamped portion of the diaphragm 10, the flange and the wall of casing 11, the hole 81, a taper slot 82 in the screw 83 which thread into cover plate 31 and counter-bore 84 closed by a 10 plug 85 threadedly engaging the cover plate 31. From the counter-bore 84 the air path is formed by conduits 86 and 87, conduits 88, 89 and 90 terminating at the face of plug 30, the screw 83 being adjusted so as to form an air passage corresponding to the amount of air passing through the path afforded around the shaft 29 in hole 45 connecting chamber CH to chamber CH2 with the result that the air pressure in these chambers is not affected by the removal of plug 30. Another 20 air path from chamber CH2 to the face of a plug 85 is formed by a conduit 91 so that upon the removal of plug 85 as for the adjustment of the air path afforded by the tapered slot 82 in screw 83, the amount of air escaping from chamber CH1 25 into the counter-bore 84 is compensated by a similar amount of air escaping from chambers CH—CH2 through the conduit 91 with the result that the air pressure in the chambers CH and CH1—CH2 is not affected by the removal of this 30 plug.

Minor changes may be made without departing from the spirit of the invention.

What is claimed is:

1. A pneumatic operated signaling device comprising a plurality of air chambers, a plurality of disengaged contacts in one of said chambers, a yieldable partition serving as a common wall between two of said chambers and operable upon a pressure difference in said chambers for engaging one of said contacts and means in said chamber actuated by the movement of said contact for indicating such pressure.

2. A pneumatic operated signaling device comprising a plurality of air chambers, a diaphragm forming a common wall for said chambers, an auxiliary chamber, a shaft extending from one of said air chambers to said auxiliary chamber, means operatively connecting said shaft to said diaphragm, contact devices in said auxiliary chamber actuated by the movement of said shaft and means in said chamber operating previous to the operation of said contacts for indicating the pressure in either one of said chambers.

3. A pneumatic operated signaling device comprising a plurality of air chambers, a yieldable partition forming a common wall for said chambers, another chamber, a shaft extending from one of said chambers to the last mentioned chamber and actuated by said diaphragm upon a pressure difference in said chambers, normally disengaged contacts in the last mentioned chamber, means defining a pointer and a gearing mechanism operable upon a movement of said shaft for indicating the pressure difference in said chambers, the continued movement of said mechanism being effective to engage said contacts.

4. A pneumatic operated signaling device comprising a plurality of air chambers, a diaphragm forming a common wall for said chambers, an auxiliary chamber, a shaft extending from one of said air chambers to said auxiliary air chamber, means in one of said air chambers operatively connecting said shaft to said diaphragm, said diaphragm operating upon a pressure difference 75

in said chambers for actuating said shaft, normally disengaged contact members in said auxiliary chamber, means carried by said shaft for engaging said members, means operated by the movement of said shaft for indicating the movement of said diaphragm, and means for adjusting the engaged relation of said contacts with respect to the second mentioned means.

5. A pneumatic operated signaling device comprising a plurality of air chambers, a diaphragm forming a common wall for said chambers, an auxiliary chamber, a plurality of normally disengaged contact devices in said auxiliary chamber.

ber engaged through the operation of said diaphragm upon a pressure difference in said chambers, means operable for adjusting the engaged relation of said contact devices, a plug in the wall of said auxiliary chamber removable for effecting such adjustment, and a system of ports connecting said chambers with said auxiliary chamber and effective upon the removal of said plug to prevent the unbalance of air pressure in each chamber.
